UNITED STATES PATENT OFFICE.

CHARLES W. DORRICOTT, OF PHILADELPHIA, PENNSYLVANIA, ASSIGNOR TO ELECTRELLE COMPANY, OF PHILADELPHIA, PENNSYLVANIA, A CORPORATION OF PENNSYLVANIA.

ELECTRIC SELF-PLAYING GRAND PIANO.

1,213,166.

Specification of Letters Patent. Patented Jan. 23, 1917.

Application filed July 3, 1912. Serial No. 707,523.

To all whom it may concern:

Be it known that I, CHARLES W. DORRICOTT, a citizen of the United States, residing at Philadelphia, in the county of Philadelphia and State of Pennsylvania, have invented new and useful Improvements in Electric Self-Playing Grand Pianos, of which the following is a specification.

My invention relates to self-playing grand pianos, and to mechanism for playing the same by aid of electro-magnets.

My invention comprehends quite a number of improvements relating mainly to the magnet bar and mechanism associated immediately with the same.

My invention further comprehends various devices for adjusting the movable armatures, and also for regulating at will the length of the tapes employed to connect the actuating shoes, controllable by the armatures, with the lever mechanism for actuating the hammer action of the piano.

My invention also relates to the manner in which the various parts are mounted within and upon the magnet bar in order to facilitate the accessibility of such parts and to promote the ease with which they may be adjusted, removed or replaced.

My invention further relates to the various improvements for increasing the efficiency of mechanisms of this kind.

Reference is made to the accompanying drawings forming a part of this specification, and in which like letters indicate like parts.

Figure 1 is a side view, partly in elevation and partly in section, showing my improved mechanism as applied to a grand piano, and also showing how the motor mechanism is conveniently driven by a primary battery. Fig. 2 is a fragmentary vertical longitudinal section through a grand piano provided with my invention. Fig. 3 is a detail showing in section the magnet bar and various parts carried thereby or adjacent thereto. Fig. 4 is a fragmentary inverted plan, or bottom view, of the magnet bar and parts connected therewith. Fig. 5 is a fragmentary section through another form of my device showing the armature mechanism as differing slightly from that shown in Fig. 3. Fig. 6 is a detail showing in cross section one of the actuating shoes, and a clip carried by it for controlling the length of one of the actuating tapes. Fig.

7 is a perspective showing one of the actuating shoes.

The casing of a grand piano is shown at 8, and is provided with a horizontally disposed board 9 serving as a key bed. Above 60 this board are the key levers, one of which is shown at 10. A hammer action appears at 11, and is provided with hammers, one of which is shown at 12. Above the hammers are strings, one appearing at 13, and in 65 connection with the strings are dampers, one being shown at 14.

Each damper 14 is connected with a damper lever 15 by aid of a rod 16. Each damper lever 15 is provided with a projecting portion 17 which carries a stop pin 18, the lower part of this pin being provided with felt. A stop plate 19 is secured upon a fastening 20 and serves as a stop for the stop pins 18. Each key lever 10 is provided at its rear end with a shoulder 21 which is arranged to be engaged by the striker bar 22 extending through a hole 23 in the key-bed 9, there being as many striker bars and as many holes as there are key levers 10. Each striker bar 22, consists of a reduced portion in the form of a stem which carries an enlarged portion 24 at its upper end, the said reduced portion or stem extending through an opening in a plate 25, 85 as more clearly shown in Fig. 2, the said plate serving as a guide for the striker bar during the movements thereof and also as a limiting stop for the striker bar, since the enlarged portion 24, thereof normally rests 90 upon the plate when the bar is inactive. Each striker bar is provided at its lower end with a head 26, and pivoted to this head is a lever 27, the number of levers 27 corresponding to the number of lever keys 10. 95 Each lever 27 is mounted upon a pivot pin 28, the latter being carried by a bracket 29, the several brackets being mounted upon a cross bar 30, as shown.

Supporting brackets 33 sustain the weight 100 of the magnet bar 49, as hereinafter explained, and are connected to said magnet bar by bolts 31. Each supporting bracket 33 is mounted upon a supporting bar 32, the latter being provided with teeth 34, and the supporting bracket 33 being similarly provided with mating teeth, as will be understood from Fig. 2. The supporting bracket 33 is provided with a threaded stem 35, and fitting upon the latter is a nut 36, the stem 110

35 extending through a slot in the supporting bar 32. By loosening the nut 36 the bracket 33 may be adjusted up or down relatively to the supporting bar 32, and then clamped in position by rotation of the nut 36. The upper end of the supporting bar 32 is disposed adjacent to a bracket 32^a, and extending through this bracket is a threaded stem 32^b. The threaded stem is provided 10 with revoluble nuts 32^c disposed upon opposite sides of the bar 32. By turning the nuts 32^c the position of the bar 32 relatively to the stem 32^b may be shifted within reasonable limits, the general position of the bar 15 32 relatively to the board 9 being thus adjustable relatively to the levers 27. There are preferably two of the brackets 33, bars 32 and brackets 32^a, but the number may be increased at will.

20 Extending upwardly from the brackets 33 are arms 37, and journaled upon the latter is a power shaft 38. Located at one end of this power shaft is a pulley 38^a (see Fig. 1) by aid whereof the power shaft is turned.

25 The form of the actuating shoes may readily be understood from Fig. 7. Each actuating shoe is provided with a thick portion 39^a, and this portion carries a leaf spring 40. Connected with each leaf spring 30 40 is a tape 41 which extends through the slots 42, 43 in the leaf spring, as will be understood from Figs. 4 and 6. Each leaf spring 40 is held in position by aid of a fastening 44. In order to tighten the tapes 35 41 all that is necessary is to pull upon their lower ends or at the most to gently press the springs 40 downward a little at their outer or free ends, and then adjust the tapes. The return of the leaf springs 40 to their normal 40 position serves to secure the tapes. Each leaf spring 40 is provided with two ears 45 integral with it, and extending from its opposite edges, these ears serving to slidably engage the thick portion 39^a of the actuating 45 shoes and to prevent lateral movement of the springs 40 relatively to said shoes. Each actuating shoe 39 is provided with an arcuate portion 46, the latter carrying a frictional contact surface 47. Each actuating 50 shoe is provided with a hole 48 for receiving a pivot pin, as will be understood from Fig. 7.

The magnet rail is shown at 49, and has generally the form of an elongated box 55 which is made of magnetic material. Mounted upon the magnet rail is a bar 50 which is adjustable slightly in a direction crossing the length of the bar, and serves the purpose of a check, or limiting stop, for the actuating shoes. Located within the magnet rail is a plate 52, and disposed between this plate and the opposite wall of the magnet bar are the magnets which are shown at 53. The plate 52 is of insulating material, and is 60 cutaway slightly, as indicated in Fig. 3, a

conductor strip 54 being inserted into the plate 52 where thus cutaway. The plate 52 has a width a little less than the length of the magnets 53, and owing to this fact there is a little space at the lower edge of the 70 plate 52. Disposed within this space is an electric cable 55, containing a number of separate wires 56 which are severally connected with the respective magnets 53. Wires 57 also connected with these magnets 75 lead therefrom to the contact strip 54.

A plurality of L-shaped brackets 58, preferably stamped from sheet metal, are secured on the lower side of the magnet rail 49, see Figs. 3 and 4, a leg of each bracket 80 extending under one of the magnets 53. Below each magnet 53 is an armature 63, through the outer end of which passes a screw bolt 67, the head 69 of which acts as a stop to prevent the armature contacting 85 with the magnet core. Fastened on the under side of the armature near its hinged end is a yoke 64 that extends beyond the free end of said armature and has two upwardly projecting arms 65 that support the actuating shoe 39 pivoted at 66 to said arms. The screw bolt 67 projects through an opening in the yoke 64 and by means of a nut 68 on said bolt, the yoke is raised and lowered and the position of the actuating shoe relatively to the shaft 38 adjusted. A screw 58^a carried by the bracket 58 and adjustable therein is connected to one end of a spring 58^b, the other end of which is attached to the yoke 64 or armature 63 to retract said parts when the magnet is deenergized. A second screw 60 adjustable in the bracket 58 has a head 62 that serves as a back stop for the armature and yoke. A pad 61 is secured on the yoke above the head of screw 60 to 105 muffle any sound when the yoke and screw come into contact. By this arrangement of parts, the bracket 58 may be secured to the magnet rail 49 by a single fastening, as a screw (in practice two screws are employed) 110 and carries the shoe, the armature, the hinge construction and various adjusting devices all in the form of a single composite unit. This feature is of great advantage in assembling the parts, in making repairs and in 115 the manufacture of instruments.

In Fig. 5 is shown a slightly different form of armature mounting. A bracket 75, made of metal, is held upon the lower portion of the magnet rail by a bolt 76, a leaf spring 77 being secured upon the bracket 75 and mounted upon this leaf spring is the armature 78. Extending through this armature is an adjusting screw 79. Revolubly fitted upon this adjusting screw is a nut 81 120 which is adapted to engage a yoke 82, this yoke being provided with a hole through which the screw 79 extends. The yoke 82 carries the boss 82^a located upon its underside. The yoke 82 is provided with arms 83 125

carrying a pivot pin 84 and journaled upon the latter is the actuating shoe 39. The adjusting screw 79 has a head 85, which may be padded, and is adapted to engage the adjacent portion of the magnet rail 49.

Any convenient form of back-stop, such as a screw bolt 87, provided with a head 89 may be provided to limit the retraction of the armature and the distance separating the actuating shoe 39 from the shaft 38. The screw bolts 87 are thus arranged in a row so that the several heads 89 are in alinement with the several bosses 82^a carried by the yokes 82. By adjusting the screw 79, by aid of the nut 81, the play of the armature 78 relatively to the magnet rail and the shoe relatively to the shaft 38 is controlled at will. A further adjustment of the armature is attained by adjusting the screw bolt 87 relatively to the rail 86 and securing the screw bolt in position after such adjustment by any suitable means. The armature 78 is yieldingly attached to the bracket 75 by the leaf spring 77. The rail 86 may be supported by any suitable means, such as by two or more brackets similar in construction to the brackets 58 that support the stop screws 60, as shown in the construction illustrated in Figs. 3 and 4. Whenever the magnet 53 is energized it actuates the armature 78, and as this armature carries the yoke 82, the yoke swings upward upon the leaf spring 77 as a center, so that the upper or arcuate surface of the actuating shoe is brought against the power shaft 38.

For the purpose of turning the power shaft 38 I provide a belt 89 (see Fig. 1) which engages the pulley 38^a and is connected with a pulley carried by a motor 90. Connected with this motor is a cable 91 which leads to a primary battery 92.

The operation of my device is as follows: The parts being arranged as above described, and the circuit through the electro-magnet being connected up in the usual or any desired manner to a contact device (not shown) for the purpose of enabling the magnets to be energized and de-energized by a music sheet and tracker board, or by any equivalent arrangement, and the motor 90 being driven by aid of the battery 92, the work of my improved mechanism will be understood. Each time a magnet 53 is energized it attracts its armature and causes the yoke, carried by said armature, to swing upward and force the adjacent actuating shoe into engagement with the power shaft, this shaft having a rotary motion (clockwise according to Figs. 3 and 5), and causing the actuating shoe to kick to the left, that is in a contra-clockwise direction, so as to exert a sharp and sudden pull upon the corresponding tape 41. This tape thereupon pulls upon the corresponding lever 27, and by tilting this lever forces the correspond-

ing striker rod upward, thereby exerting a pushing force against a key lever 10, and actuating it and the hammer action associated with the key in question, and causing the proper string 13 to be struck. The damper action is operated directly by the key lever. As the key lever is tilted the shoulder 21 engages the projection 17 and tilts the damper lever 15 which by pressing upward against the damper rod 16 lifts the damper 14 from the string. When the circuit through the magnet is broken the parts drop back to their respective normal positions.

It will be noted that the levers 27 (see Fig. 2) are located below the board 9 and consequently outside of the piano casing. They are thus situated in a good position to facilitate the fastening of the tapes 41 upon them, or for detaching said tapes, as desired. By virtue of this fact the power shaft, magnet rail, and other parts of the player mechanism may readily be placed upon a piano already built or even in use with the necessity of but little change in order to apply these parts.

It will also be noted that as the tape 41 is a flexible connection and exerts a suspensory action upon the actuating shoe 39, this shoe does not bear any weight of any of the parts, and consequently has great freedom and mobility of action so that its movements take place with precision. Except for the use of the flexible connections consisting of the tapes 41, the weight of the striker rods 100 22, rear ends of the key lever 10 and various other parts, would rest directly upon the actuating shoes and interfere to a greater or lesser extent with the action of the latter. Indeed with this arrangement a part of the weight of the actuating shoes is transferred to the levers 27, and this is of advantage owing to the fact that the actuating shoes are brought more readily and completely under control of the power shaft.

It will also be noted that the supporting bar 32 is adjustable relatively to the stem 32^b so that the power shaft, magnet rail, and various parts grouped therewith, are as a unit adjustable toward or from the group 115 of levers 27, as will be understood from Fig. 2. This enables the flexible connections to be directed at different angles relatively to the levers 27 and constitutes in effect a form of adjustment. Besides this the bracket 33, 120 being adjustable relatively to the supporting bar 32, enables the power shaft, magnet rail, and various other parts to be adjusted to different elevations relatively to the piano. The several flexible connections are individually adjustable as above described, as they can be drawn to any desired extent through their respective leaf springs 40 and secured by tension of the same.

Mounted below the board 9 is a rocking 130

shaft 93, carrying an arm 94. Pivotally connected with this arm is a rod 95 which extends upwardly and controls a plurality of leaf springs 96, one for engaging each piano key. A second arm 97 on the shaft 93 is pivotally connected to a sliding bar 98; the latter is pivotally connected to a short lever 99. This lever is mounted upon a pivot pin 100 and is adapted to be rocked upon its mounting by hand. The operator by swinging the short lever 99 moves the rod 98 lengthwise and rocks the shaft 93 so as to bring the leaf springs 96 severally into or out of engagement with the piano keys. The piano may thus be shifted from a condition for automatic playing for one for hand playing. The leaf springs by pressing gently upon the piano keys cause the rear end of the keys to maintain good contact with the upper ends 24 of the striker bars 22, thus preventing lost motion. As a consequence the frequency with which the keys may be actuated without impairment to their functions is greatly increased. For instance, a particular key being pressed upon by its particular spring is held with a gentle pressure upon the corresponding striker bar. If now, under control of the playing mechanism the striker bar moves upward say two or three strokes in rapid succession, upon each descent of the striker bar it is followed closely by the rear end of the key so that there is no lost motion and no loss of time due to any lagging action by the key in following the striker bar. This is of very great importance where the music is to be played rapidly or where a particular note is repeated in rapid succession. Except for the leaf springs taking care of this matter as above explained not only would the undesirable lost motion be developed, but even false rattling sounds of a mechanical nature might be introduced.

Having thus described the invention what is claimed as new is:

1. An electrically operated player for musical instruments comprising a plurality of levers, means for pivotally mounting the same upon the underside of a piano, striker rods connected with said levers and extending through the bottom of said piano into engagement with the key levers thereof, mechanisms for actuating said levers, and a flexible connection between each lever of the plurality of levers and an actuating mechanism.

2. An electrically operated player for musical instruments comprising striker rods for engaging the actuating elements of the instruments, a plurality of levers connected with said striker rods, a rail supporting said levers, actuating shoes, flexible connections between said levers and the actuating shoes, a power shaft for swinging said actuating shoes, and electrically operated means for

forcing said actuating shoes into engagement with said power shaft.

3. The combination with a piano casing, a hammer action mounted therein, and key levers for actuating said hammer action, of striker rods arranged to actuate said key levers, levers without the casing connected to said striker rods, actuating shoes, a flexible connection between each lever and an actuating shoe, a rotating shaft, and electromagnetic devices each supporting one of said shoes and adapted to move the same into engagement with said rotating shaft. 70 75

4. The combination with a piano casing, a hammer action mounted therein, and key levers for actuating said hammer action, of striker rods arranged to actuate said key levers, levers without the casing connected to said striker rods, actuating shoes, a flexible connection between each lever and an actuating shoe, a rotating shaft, electromagnetic devices including armatures upon which said shoes are pivotally mounted, and means for energizing said magnets to cause the engagement of the actuating shoes with the 80 85 90 rotating shaft.

5. The combination with a piano casing, a hammer action mounted therein, and key levers for actuating said hammer action, of striker rods arranged to actuate said key 95 levers and having a limited downward movement, levers connected to said striker rods, actuating shoes, a flexible suspending member between each lever and an actuating shoe to relieve said shoes of the weight of said 100 key levers and associated parts, a rotating shaft, and electrically operated means for moving said actuating shoes into engagement with said shaft. 105 110

6. A grand piano having an electrically 105 operated playing mechanism associated therewith, said mechanism being located below the key bed of the piano and comprising a plurality of vertically movable striker rods extending up through openings in the 110 key bed, levers pivotally supported below the key bed and to which said rods are respectively pivoted, a power shaft, inverted actuating shoes arranged below said power shaft, a flexible connection between each 115 shoe and its associated lever, and electro-mechanical means for bringing said actuating shoes into and out of engagement with the power shaft. 120

7. The combination of a musical instrument provided with keys and a casing, supporting bars carried by said casing and adjustable thereon, brackets mounted upon said supporting bars and independently adjustable bodily along the same, player mechanism mounted upon said brackets and adjustable therewith relatively to said supporting bars, and connections from said player mechanism to the keys of the musical instrument. 125 130

8. The combination with a piano casing and an action including keys, of striker rods for actuating said keys, levers located below said piano casing and connected to said striker rods, actuating shoes, flexible connections therefrom to said levers, a magnet rail located below said levers and supported by the piano casing, said magnet rail having the form of a box and open at its bottom, electro-magnets mounted within said magnet rail and disposed vertically, armatures sustained by said magnet rail below the electro-magnets and pivotally supporting said actuating shoes, and a rotatable shaft for actuating said shoes when brought into engagement therewith by said electro-magnets.

9. The combination of an actuating shoe, a power shaft for causing the same to swing, an armature provided with means for moving said actuating shoe into and out of engagement with said power shaft, a spring clip mounted upon said actuating shoe, a flexible connection extending through said spring clip and held by pressure thereof against said actuating shoe, and mechanism controllable by said flexible connection for actuating a musical instrument.

10. The combination of a power shaft, an actuating shoe movable toward and from the same, mechanism controllable by said actuating shoe for causing a musical instrument to sound, an armature provided with

means for shifting said actuating shoe against said power shaft, a bracket for supporting said armature and having a portion extending beneath the same, an adjusting screw extending through said portion, and a spring connected with said adjusting screw and with said armature, for tensioning the latter.

11. The combination of a power shaft, an actuating shoe movable toward and from the same, mechanism controllable by said actuating shoe for causing a musical instrument to sound, an armature provided with means for shifting said actuating shoe against said power shaft, a bracket for supporting said armature, said bracket having a portion extending therefrom and bent substantially into U-shape, a back stop carried by said portion of said bracket for stopping movements of said armature in one direction, a spring connected with said portion and with said armature for retracting said armature, a magnet rail for supporting said bracket, and an electromagnet carried by said magnet rail for attracting said armature.

In testimony whereof I have hereunto set my hand in presence of two subscribing witnesses.

CHARLES W. DORRICOTT.
